UNITED STATES PATENT OFFICE.

ALBERT J. MEIER, OF GLENDALE, MISSOURI, ASSIGNOR TO UNIT CONSTRUCTION COMPANY, OF WILMINGTON, DELAWARE, A CORPORATION OF DELAWARE.

CONCRETE CONSTRUCTION.

1,008,606.

Specification of Letters Patent. Patented Nov. 14, 1911.

Application filed November 16, 1909. Serial No. 528,272.

To all whom it may concern:

Be it known that I, ALBERT J. MEIER, a citizen of the United States, residing at Glendale, in the county of St. Louis and 5 State of Missouri, have invented certain new and useful Improvements in Concrete Construction, (Case A,) of which the following is a specification, reference being had therein to the accompanying drawings.

10 This invention relates to concrete building structures and refers particularly to a construction in which concrete floor and ceiling members are supported by uprights or columns and are united integrally together to 15 form a rigid and unitary structure.

It is the object of this invention to provide a concrete structure in which the reinforcing bars projecting from abutting, adjoining, or oppositely-disposed members are 20 united integrally together.

In the drawings forming part of this specification, in which like numbers of reference denote like parts wherever they occur, Figure 1 is a plan view; Fig. 2 is a sectional view on the line 2—2, Fig. 1; Fig. 3 is a plan view; and Fig. 4, is a fragmentary view partly in section, showing the relationship between the slabs and the beams.

In Figs. 1 and 2, a pair of beams 1 is depicted, the same being supported by a column 2. Each of said beams 1 is preferably provided with the shoulders 3 and a tenon 4. A gusset 5 or a plurality of such gussets are formed on column 2. Each 35 gusset 5 is provided with a cut-away portion 6 which communicates with a slot 7 in the end of a beam 1. A reinforcing bar 8 having its ends embedded in said column is adapted to project from said column into 40 slots 7 in each beam. Each tenon 4 is provided with a reinforcing bar or bars 9 which project from each end thereof. Each bar 9 projecting from the end of one of said tenons overlaps an end of a similar bar projecting from the other said tenon, and said 45 overlapping ends are welded or brazed together electrically or in any other suitable manner, whereby said bars are united securely together and form a continuous bar. 50 Reinforcing bars 10 are embedded in the lower part of said beam, and, adjacent the ends thereof one or more of said bars 10 turn upwardly and project from beam 1. Each bar 10 projecting from the end of one 55 of said beams overlaps an end of a similar

bar projecting from the other said beam, and said overlapping ends are secured together by welding or brazing. Each cut-away portion 6 is covered by a so-called form (not shown in the drawings) and said 60 slots and cut-away portions are filled with grout or wet-concrete which is allowed to set therein and unites said beams and said column integrally together. A flange 11 of each slab 12 rests on a shoulder 3 of a beam 65 1 and against tenon 4. Said flange 11 raises the top surface of slab 12 to a greater distance above shoulder 3 than the distance the tenon 4 projects above said shoulder, so that, when a slab is placed upon each shoulder 3 of a beam 1, a space 13 above said 70 tenon is left between the two slabs supported by said beam. Reinforcing bars 14 are embedded in said slab 12 and those bars 14, which extend at an angle to space 13, 75 project from each slab into said space. Each bar 14 projecting from one of said slabs into space 13 overlaps a similar bar 14 projecting from an adjacent slab and said overlapping bars are secured together by 80 welding or brazing, whereby said bars are made continuous and said slabs are connected firmly together. Grout or wet-concrete is poured into space 13 and, when set therein, unites said slabs and said beam to form a 85 unitary structure.

In Fig. 3, the column 2 is surmounted by a cap 15 upon which flange 11 of each slab 12 rests. The slabs 12 join each other without an intermediate space for the formation of a beam, but cut-away parts 16 in each slab at the corner adjacent a supporting column unite to form a cruciform space partly over said cap 15 and partly with an open bottom, which must be temporarily closed with a board or former. Reinforcing bars 17 extend into said cruciform space from said slabs. Each bar 17 projecting from one of said slabs into said cruciform space overlaps an end of a similar bar 17 projecting from an adjacent slab into said cruciform space, and said overlapping ends are welded or brazed together, thereby making said bars continuous. Grout or wet-concrete is poured into said cruciform space, and sets therein, being supported while plastic by said cap and the board or former held under the bottomless part of said space, and unite the four slabs surrounding said cruciform space and said column integrally together. 105 110

I claim:

1. A concrete structure including a column forming a support, a plurality of members supported from the support and having portions adjacent the support providing a space between the members which space overlies the support, and a series of reinforcing bars projecting outwardly from each of the members, the bars of opposite members being arranged to aline and overlap each other in said space and having said overlapping ends integrally connected thereby providing two series of bars each having portions of double thickness which overlie the support, the double portions of one series crossing the double portions of the other series at points over the support.
2. In a concrete structure, a support, a plurality of slabs each having a portion resting on said support, said portions adjacent

the support providing a space which overlies the support, and a series of reinforcing bars carried by each slab and extending into said space, the bars of opposing slabs being in overlapping engagement and rigidly secured to each other whereby the respective overlapping bars form continuous integral one piece bars having portions of double thickness, which portions of double thickness are disposed in said space, and grout engaging the slabs and filling said space, and inclosing the exposed portions of the bars, the bars of the opposed slabs crossing each other.

In testimony whereof I have affixed my signature in presence of two witnesses.

ALBERT J. MEIER.
